UNITED STATES PATENT OFFICE.

GEORGE W. DONNING, OF EAST ORANGE, NEW JERSEY, ASSIGNOR OF
ONE-HALF TO HARRY T. AMBROSE, OF ORANGE, NEW JERSEY.

TYPE-WRITER.

SPECIFICATION forming part of Letters Patent No. 745,163, dated November 24, 1903.

Application filed June 21, 1901. Serial No. 65,468. (No model.)

To all whom it may concern:

Be it known that I, GEORGE W. DONNING, a citizen of the United States, residing at East Orange, in the county of Essex and State of New Jersey, have invented certain new and useful Improvements in Type-Writers; and I do hereby declare the following to be a full, clear, and exact description of the invention, such as will enable others skilled in the art to which it appertains to make and use the same.

This invention relates to an improved type-bar carrying a multiple type-head for type-writing machines which shall be compact, durable in construction, and certain in operation.

My invention further relates to a construction in which interference or impact between descending and ascending type-heads will cause the ascending type-head to shift sufficiently to prevent interlocking and jamming of such interfering type-heads, while the descending type-head will be positively locked against shifting thereby.

My invention further relates to an improved actuating mechanism for type-bars.

My invention consists in the constructions, combinations, and arrangements herein described and claimed.

In the accompanying drawings, forming a part of this application, and in which similar reference-symbols indicate corresponding parts in the several views, Figure 1 is a sectional elevation of a type-writing machine, illustrating one form of my improved type-bar and its actuating means. Fig. 2 is a detail elevation, on a larger scale, of a type-bar and its key mechanism shown in Fig. 1. Fig. 3 is a side elevation of a preferred construction of type-bar. Fig. 4 is a front elevation of the type-bar. Fig. 5 is a detail sectional view showing a preferred form of multiple type-head. Fig. 6 is a side elevation of a guide-yoke for the type-bar provided on its under surface with a spring for preventing shocks and for effecting quick return of the type-bar. Fig. 6^a is a bottom plan view of the guide-yoke illustrated in Fig. 6. Fig. 7 is a side elevation showing a modified form of guide-yoke. Fig. 8 is a de-

tail side elevation showing a modified form 50 of type-bar and actuating mechanism, and Fig. 9 is a plan view showing a segmental shifting-plate provided with friction-rollers.

Referring especially to Figs. 1 and 2 of the drawings, in which I have illustrated a flat-platen or book type-writer, A indicates a type-bar of any desired shape, pivotally carrying a multiple type-head a¹², shown provided with three type-holders a¹⁷ and with a rearward extension a¹⁴. A serrated link a¹⁰ is 60 shown pivotally connected to the extension a¹⁴ and to a rock-arm a⁶, which latter is pivotally carried on the type-bar. The link a¹⁰ is provided with an actuating-tailpiece a¹⁸, constructed to engage a shiftable member C upon 65 movement of the type-bar. A spring member a¹⁹ is secured to the type-bar in position to engage the serrations of link a¹⁰ and positively lock said link in its adjusted position. This spring member a¹⁹ is preferably constructed with a slotted portion to receive the link a¹⁰ and with a rearward-extending portion a²¹, arranged to engage a type-head releaser a²² when the type-bar is in its upward 70 normal position. A spring a⁸, carried by the type-bar, is shown connected to the rock-arm a⁶ and acts to return the type-head to its normal position when the spring member a¹⁹ is released from engagement with the serrated link a¹⁰.

The lower end of the type-bar is pivoted at a²⁶ in a guide-yoke a², shown secured to a base-plate B by a screw b. This guide-yoke is preferable to the usual pivot or cone-bearing support in that it provides a broad guiding-surface for the type-bar throughout the latter's entire arc of movement, thus preventing lateral play of the type-bar with slight friction. A rod or link a^{4X} is shown connecting a toe a³ on the type-bar with the inner arm of a key-lever D. Suitable means, such as a turnbuckle, may be provided for adjusting the length of the rod a^{4X}. A spring c^{18X}, connecting the inner end of the key-lever with the type-head releaser, acts to return 95 said key-lever to its normal position upon its release.

The guide-yoke may carry a resilient mem-

ber a^{23} , as shown in Figs. 6 and 6^a, in position to engage the type-bar upon movement of the latter, and thereby prevent the type from striking the platen with a jarring action.

5 The resilient member a^{23} acts also to produce quick return of the type-bar to its normal position by engagement with the forward face of the tailpiece of the type-bar.

If desired, I may provide the guide-yoke 10 with a stop or abutment a^{24} , as shown in Fig. 7, against which the type-bar will strike on its return to normal position.

The actuator for operating the actuating-tailpiece a^{13} preferably comprises a shiftable 15 segmental bar C, carried by hangers or rods c, which latter are guided in openings formed in the base-plate B and type-head releaser a^{22} or in any convenient portion of the type-writer frame.

20 A shaft c^2 , extending transversely of the type-writer, carries adjacent each end a bell-crank lever c^4 , one arm of each bell-crank lever being connected to one of the hangers c. The other arm of each bell-crank lever is 25 preferably connected by a link c^6 to an arm c^5 , secured on a second transverse shaft c^3 , this second shaft carrying a crank c^7 , which is connected to one of the hangers c. An arm c^8 is secured to the shaft c^2 , preferably 30 near one end thereof, and pivotally supports two slotted links c^9 c^{10} .

A shift-key lever E for capital letters carries a pin extending within the slot of the link c^9 , and a shift-key lever F for numerals 35 and symbols carries a pin extending within the slot of the link c^{10} , the pin on the shift-lever F swinging on a larger radius than the pin of the cap-lever, as clearly shown in Fig. 1.

It will be understood that upon actuation 40 of the cap-key lever E the operating segmental bar C will be raised to its intermediary position and that upon actuation of the numeral-key lever F the segmental bar will be raised to its highest position. It will further 45 be clear that upon actuation of the cap-key lever the pin of the numeral-key lever will slide in its engaging slot, and vice versa, so that actuation of either of said shift-levers will in no manner affect the other. Upon release of the shift-levers the segmental bar and 50 its attached parts may be returned to their normal lowest position by gravity or by a spring.

When it is desired to print a lower-case 55 character, the key-lever D is actuated to swing the type-bar downward and bring the lower-case type in contact with the paper. The segmental bar C being in its normal lowest position will not engage the tailpiece a^{13} 60 to shift the type-head.

When an upper-case character is to be printed, the cap-lever E is actuated to shift the segmental bar C to its intermediary position. The key-lever D is thus actuated to 65 swing the type-bar downward, whereupon the tailpiece a^{13} will engage the bar C and adjust

the type-head sufficiently to bring the upper-case type into printing position. The spring member a^{19} , engaging the serrated link a^{10} , positively locks the type-head in its adjusted 75 position against turning movement in the direction of the hands of a watch, as shown in Figs. 1 and 2. Upon release of the key-lever D the type-bar returns to its normal upright position and the rearward projection 75 a^{21} of the spring member contacts with the type-head releaser a^{22} and forces the spring member from engagement with the serrated link a^{10} , thus permitting the spring a^8 to swing the type-head into its normal position. 80 Should the bar C be in raised position during such return of the type-bar, the tailpiece a^{13} will readily ride over the inclined face thereof.

If a numeral is to be printed, the numeral shift-key F is actuated to shift the segmental 85 bar C to its highest position, whereupon during the downward swing of the type-bar the tailpiece a^{13} will engage the segmental bar and adjust the type-head to bring the numeral-type into printing position, the spring member a^{19} positively locking the type-head in its adjusted position, as previously described.

While I have illustrated my invention applied to a type-head provided with three type, 95 it is obvious that a greater or less number may be employed, if desired.

Fig. 5 illustrates a preferred construction of multiple type-head, which consists of the head proper a^{12} , provided with a plurality of 100 type holders or sockets a^{17} , the head being provided with grooves or saw-cuts between the sockets, whereby the latter are rendered yielding and may be bent to position for proper alinement.

Fig. 8 illustrates a modified form of type-bar and actuating mechanism in which a pawl a^{35} on the type-bar engages teeth a^{34} on the type-head to positively lock the latter in its several positions, a spring a^{36} being provided 110 to maintain the pawl in engagement with said teeth. The pawl a^{35} is provided with a rearward-extending portion which is arranged to engage the type-head releaser a^{22} when the type-bar is in its normal upright 115 position, and thereby release the pawl from engagement with the teeth a^{34} .

The operating mechanism of the type-bar illustrated in Fig. 8 constitutes a lever c^{16} , pivoted in a bearing c^{15} on the base-plate B 120 and connected to the toe of the type-bar by a link c^{17} , the link c^{16} being connected by a rod a^{4X} with the inner end of a key-lever, as clearly shown. This construction obviates the employment of a bent rod a^{4X} , as in the 125 construction of Figs. 1 and 2, and also permits the use of a longer key-lever and insures an easier touch. If desired, the bearing c^{15} of these several type-bar-actuating mechanisms may be formed in one continuous comb-like 130 piece.

Fig. 9 illustrates a modified form of shift-

able segmental bar C in which a friction-bearing, such as a roller c¹⁴, is provided for each type-bar.

It is obvious that one advantage of my improved construction is that should interference or impact occur between descending and ascending type-heads the ascending type-head will be free to shift sufficiently to pass a descending type-head, while the latter will be positively locked against shifting by such impact.

Having thus fully described my invention, what I claim as new, and desire to secure by Letters Patent, is—

15 1. In a writing mechanism, the combination of a type-bar, a multiple type-head pivotally carried thereon, actuating mechanism carried by said type-bar for adjusting the type-head, a link connecting said actuating mechanism and type-head, and locking means carried by the type-bar and engaging the said link intermediary of said actuating means and type-head to positively lock the same in its adjusted positions, substantially as described.

20 2. In a writing mechanism, the combination of a type-bar, a multiple type-head pivotally carried thereon, actuating mechanism carried by said type-bar for adjusting the type-head, a link connecting said actuating mechanism and type-head, locking means carried by the type-bar and engaging the said link to positively lock the same in its adjusted positions, and means carried by the type-bar and constructed to return the parts to their normal position, substantially as described.

25 3. In a writing mechanism, the combination of a type-bar, a multiple type-head pivotally carried thereon, actuating mechanism carried by said type-bar for adjusting the type-head, a link connecting said actuating mechanism and type-head, locking means carried by the type-bar and engaging the said link to positively lock the same in its adjusted positions, and means carried by said type-bar and engaging said actuating mechanism to return the parts to their normal position, substantially as described.

40 4. In a writing mechanism, the combination of a type-bar, a multiple type-head pivotally carried thereon, a rock-arm pivoted on said type-bar, a link connecting said type-head and rock-arm and carrying an actuating tailpiece for adjusting the link and its attached type-head, and means carried by the type-bar and engaging said link intermediary of said actuating means and type-head to positively lock the same in its adjusted positions, substantially as described.

45 5. In a writing mechanism, the combination of a type-bar, a multiple type-head pivotally carried thereon, a rock-arm pivoted on said type-bar, a link connecting said type-head and rock-arm and carrying an actuating tailpiece for adjusting the link and its at-

tached type-head, means carried by the type-bar and engaging said link to positively lock the same in its adjusted positions, and a spring carried by the type-bar and connected to said rock-arm to return the same to its normal position, substantially as described. 70

6. In a writing mechanism, the combination of a type-bar, a multiple type-head pivotally carried thereon, a rock-arm pivoted on said type-bar, a serrated link connecting said type-head and rock-arm and carrying an actuating-tailpiece for adjusting the link and its attached type-head, and means carried by the type-bar and engaging said serrations to positively lock the link in its adjusted positions, substantially as described. 75

7. In a writing mechanism, the combination of a type-bar, a multiple type-head pivotally carried thereon, a rock-arm pivoted on said type-bar, a serrated link connecting said type-head and rock-arm and carrying an actuating-tailpiece for adjusting the link and its attached type-head, and spring means carried by the type-bar and engaging said serrations to positively lock the link in its adjusted positions, substantially as described. 80

8. In a writing mechanism, the combination of a type-bar pivotally supported, means for actuating said type-bar about its pivot to writing position, a multiple type-head pivotally secured to said type-bar, actuating mechanism carried by said type-bar, a link connecting said type-head and actuating mechanism, an actuator, means constructed to shift said actuator into the path of said actuating mechanism, whereby the type-head will be adjusted upon movement of the type-bar about its pivot, and locking means carried by the type-bar and engaging said link intermediary of said actuating means and type-head to positively lock the parts in their adjusted positions, substantially as described. 95

9. In a writing mechanism, the combination of a type-bar pivotally supported, means for actuating said type-bar about its pivot to writing position, a multiple type-head pivotally secured to said type-bar, actuating mechanism carried by said type-bar, a link connecting said type-head and actuating mechanism, an actuator, means constructed to shift said actuator into the path of said actuating mechanism at a point adjacent to the normal position of said mechanism, whereby the type-head will be adjusted during early 105 movement of the type-bar about its pivot, and locking means carried by the type-bar and engaging said link intermediary of said actuating means and type-head to positively lock the parts in their adjusted positions, substantially as described. 110

10. In a writing mechanism, the combination of a type-bar pivotally supported, means for actuating said type-bar about its pivot to writing position, a multiple type-head pivot- 115 120 125 130

ally carried on said bar, a rock-arm pivoted on said bar, a link connecting said type-head and rock-arm and carrying an actuating-tailpiece, locking means carried by the type-bar and engaging said link intermediary of said actuating means and type-head to positively lock the same, an actuator, and means constructed to shift said actuator into the path of the tailpiece, whereby the link and its attached type-head will be adjusted upon movement of the type-bar, substantially as described.

11. In a writing mechanism, the combination of a type-bar, a multiple type-head pivotally carried thereon, actuating mechanism carried by said type-bar for adjusting the type-head, a link connecting said actuating mechanism and type-head, locking means carried by the type-bar and engaging the said link to positively lock the same in its adjusted positions, and means constructed and arranged to engage said locking means to maintain such locking means out of engagement with the link when the type-bar is in its normal upright position, substantially as described.

12. In a writing mechanism, the combination of a type-bar, a multiple type-head pivotally carried thereon, a rock-arm pivoted on said type-bar, a link connecting said type-head and rock-arm and carrying an actuating-tailpiece for adjusting the link and its attached type-head, means carried by the type-bar and engaging said link to positively lock the same in its adjusted positions, and means constructed and arranged to engage said locking means to maintain such locking means out of engagement with the link when the type-bar is in its normal upright position, substantially as described.

13. In a writing mechanism, the combination of a type-bar pivotally supported, means for actuating said type-bar about its pivot to writing position, a multiple type-head pivotally secured to said type-bar, actuating mechanism carried by said type-bar, a link connecting said type-head and actuating mechanism, an actuator, means constructed to shift said actuator into the path of said actuating mechanism, whereby the type-head will be adjusted upon movement of the type-bar about its pivot, and a resilient member carried by the type-bar and engaging said link to positively lock the parts in their adjusted positions, substantially as described.

14. In a writing mechanism, the combination of a type-bar pivotally supported, means for actuating said type-bar about its pivot to writing position, a multiple type-head pivotally secured to said type-bar, actuating mechanism carried by said type-bar, a link connecting said type-head and actuating mechanism, an actuator, means constructed to shift said actuator into the path of said actuating mechanism, whereby the type-head will

be adjusted upon movement of the type-bar about its pivot, a resilient member carried by said type-bar and engaging the said link to positively lock the parts in their adjusted positions, said resilient member provided with a portion extending to the rear of said link, and means constructed and arranged to engage such extending portion to maintain the locking means out of engagement with said link when the type-bar is in its normal upright position, substantially as described.

15. In a writing mechanism, the combination of a type-bar pivotally supported, means for actuating said type-bar about its pivot to writing position, a multiple type-head pivotally secured to said type-bar, actuating mechanism carried by said type-bar, a link connecting said type-head and actuating mechanism, an actuator comprising a segmental plate, means constructed to shift said actuator into the path of said actuating mechanism, whereby the type-head will be adjusted upon movement of the type-bar about its pivot, and locking means carried by the type-bar and engaging said link intermediary of said actuating means and type-head to positively lock the parts in their adjusted positions, substantially as described.

16. In a writing mechanism, the combination of a type-bar pivotally supported, means for actuating said type-bar about its pivot to writing position, a multiple type-head pivotally secured to said type-bar, actuating mechanism carried by said type-bar, a link connecting said type-head and actuating mechanism, an actuator inclined to the path of said actuating mechanism to permit such mechanism to ride over the actuator, upon contact therewith on either a forward or rearward movement of the type-bar, means constructed to shift said actuator into the path of said actuating mechanism, whereby the type-head will be adjusted upon movement of the type-bar about its pivot, and locking means carried by the type-bar and engaging said link intermediary of said actuating means and type-head to positively lock the parts in their adjusted positions, substantially as described.

17. In a writing mechanism, the combination of a type-bar pivotally supported, means for actuating said type-bar about its pivot to writing position, a multiple type-head pivotally secured to said type-bar, actuating mechanism carried by said type-bar, a link connecting said type-head and actuating mechanism, an actuator provided with friction-bearings and inclined to the path of said actuating mechanism to permit such mechanism to ride over the actuator upon contact therewith on either a forward or rearward movement of the type-bar, means constructed to shift said actuator into the path of said actuating mechanism, whereby the type-head will be adjusted upon movement of the type-bar about its pivot, and locking means car-

ried by the type-bar and engaging said link to positively lock the parts in their adjusted positions, substantially as described.

18. In a writing mechanism, the combination of a type-bar, a multiple type-head pivotally carried thereon, means constructed to actuate said type-head, means constructed to positively lock said type-head, a pivotal support for said type-bar comprising a guide-yoke, and means carried by the guide-yoke

for effecting accelerated return of the type-bar to normal position, substantially as described.

In testimony whereof I affix my signature in the presence of two subscribing witnesses. 15
